UNITED STATES PATENT OFFICE.

JOSEPH L. STUTTE, OF FLINT, MICHIGAN.

CURTAIN STRETCHER.

1,414,231.

Specification of Letters Patent. Patented Apr. 25, 1922.

Application filed July 13, 1921. Serial No. 484,354.

To all whom it may concern:

Be it known that I, JOSEPH L. STUTTE, a citizen of the United States, residing at Flint, in the county of Genesee and State of Michigan, have invented certain new and useful Improvements in a Curtain Stretcher, of which the following is a specification.

This invention relates to curtain stretchers of the collapsible type and the main object thereof is to provide a curtain stretcher adapted to be folded into small compass when not required for use, and to be readily unfolded.

Another object of the invention is to so construct a curtain stretcher that a plurality of curtains may be stretched thereon, and held out of contact with each other, to permit the passage of air between them and facilitate drying of the curtains.

Another object is to so construct a stretcher of this character, that the curtains stretched and dried thereon, will hang perfectly straight when the operation is completed.

With these and other objects in view, the invention consists in certain novel features of construction as hereinafter shown, described and claimed.

In the accompanying drawings:

Figure 1 represents a plan view or front elevation of the stretchers shown in use.

Fig. 2 is a similar view, with the stretcher in a partially collapsed position.

Fig. 3 is a similar view, showing the stretcher in a collapsed position held ready for storage or transportation; and

Fig. 4 is a side elevation, showing the stretcher in standing position for drying the curtains.

In the embodiment illustrated the stretcher constituting this invention comprises two side bars, 1 and 2, connected at their terminals by foldable end bars 3 and 4, said end bars being hingedly connected with the side bars as shown at 5, and the sections thereof connected with each other as shown at 6, the hinges being arranged reversely so that the end bars will fold inwardly relatively to the side bars and toward each other when the frame is collapsed, as is shown clearly in Fig. 2. The sections 7 and 8 of the end bars are held in open position in alinement with each other by any suitable means, hooks 9 being here shown carried by one section and engaging eyes 10, carried by the other section.

Chains 11 and 12 are attached at one end

to the outer faces of the side bars 1 and 2 and detachably engaged at their other ends with the inner faces of the end member 3, being stretched taut to hold the frame in open position.

Hingedly mounted on the rear faces of the side bars 1 and 2, are supporting legs 13 and 14, which are designed to support the frame in a vertical or substantially vertical position, when the curtains have been placed thereon ready for drying. These legs 13 and 14 are provided near their ends with eyes 15, which are designed to be engaged by hooks 16 carried by the respective side bars to hold the legs in either open or closed positions, the hooks 16 being engaged with the inner eyes 15 when the legs are open as shown in full lines in Fig. 4, and with the outer eyes 15 when said legs are folded as shown in dotted lines in said figure.

Hooks 17 are also carried by the rear face of one side bar, and are adapted to engage eyes 18 carried by the other side bar when the frame is in collapsed position as shown in Fig. 3 for holding it with the parts secured against wobbling or opening.

The side bars 1 and 2, are provided on their front faces at their opposite ends with a plurality of series of seats or notches 19 and 20, the notches of the series 19 being deeper than those of the series 20. These notches or seats 19 and 20, are designed to receive curtain carrying poles or rods 21, four of which are shown, and which are of a length to extend transversely of the frame when in open position and to project at their ends beyond the side bars thereof, as is shown clearly in Fig. 1, the undercut portions of these notches are arranged inwardly, so that when the rods 21 are mounted therein, after the curtain C has been applied thereto, the tightening of the curtain will cause the rods engaged therewith to enter said undercut seat portions, as is shown clearly in Fig. 4.

As shown, the deeper notches or seats 19 are arranged at opposite ends of the series of shallower seats 20, (see Fig. 4) and when the poles or rods 21 are mounted therein, obviously they will be held in planes, one in advance of the other, so that the curtain supported by said rods will be held out of contact.

The curtains C are here shown with hems at their opposite ends, through which the rods 21 are passed and obviously when the

rods are seated so as to stretch these curtains taut, longitudinally, they will be of uniform length and when dried and placed in use will hang evenly.

5 In the frame shown in Fig. 1 the width thereof is sufficient to accommodate a pair of curtains arranged side by side, and the arrangement of the rods in the shallower and deeper seats provides for two pairs of 10 curtains being dried on the same stretcher, one being arranged in advance of the other to permit the passage between them of air for drying.

In the use of this stretcher, the parts 15 being in collapsed, folded position as shown in Fig. 3, the hooks 17 are first disengaged from the eyes 18, and the frame opened up in the position shown in Fig. 1 and the hooks 9 engaged with the eyes 10 and the 20 chains 11 and 12 attached to the end bar 3. After the frame has been positioned thus, the legs 14 are opened to support it in upright position and secured by engaging the hooks 16 with the inner eyes 15 on said 25 legs. The rods 21 which when not in use may be strapped to the folded frame or otherwise disposed of are inserted through the hems in the curtains C and said rods are engaged with the seats 19 and 20 as 30 shown clearly in Figs. 1 and 4, the rods which are mounted in the seats 20 being held in advance of those carried by seats 19, so that the curtains mounted on said rods will be held out of contact with each other, and 35 air currents permitted to pass between them to effect quick drying. As above described the engagement of the rods with the seats at opposite ends of the side bars, the seats at one end facing in a direction opposite to

those at the other, will operate to place the 40 curtains C under tension and hold the rods against accidental detachment from the seats.

The preferred embodiment of the invention is disclosed in the drawings and set 45 forth in the specification, but it will be understood that any modifications within the scope of the claimed invention may be made in the construction without departing from the principle of the invention or sacrificing 50 any of its advantages.

What I claim is:

1. A curtain stretcher comprising side and end bars and curtain carrying rods, said side bars being provided in their front faces with a plurality of rod receiving seats of varying depths, the seats on one bar being arranged in transverse alinement with those on the other bar, said seats being adapted to receive and support the curtain carrying 60 rods to hold them in superposed planes spaced from each other to provide for the passage of air between the curtains carried by the rods.

2. A curtain stretcher comprising hingedly connected side and end bars, said end bars being composed of hingedly connected sections, means to hold said sections in extended operative position, said side bars being provided in one face thereof at their 70 opposite ends with a plurality of series of rod receiving notches of varying depths, whereby the rods are supported in planes in advance of each other, and the curtains carried by said rods held out of contact. 75

In testimony whereof, I affix my signature hereto.

JOSEPH L. STUTTE.
